UNITED STATES PATENT OFFICE

131,659

DESIGN FOR A PORTABLE POWER TOOL UNIT

Alonzo G. Decker, Baltimore County, Md., assignor
to The Black and Decker Manufacturing
Company, a corporation of Maryland

Application July 17, 1941, Serial No. 102,199

Term of patent 7 years

To all whom it may concern:

Be it known that I, Alonzo G. Decker, a citizen of the United States and a resident of Baltimore County, State of Maryland, have invented a new, original, and ornamental Design for a Portable Power Tool Unit, of which the following is a specification, reference being had to the accompanying drawing, forming part thereof.

In the drawing:

Fig. 1 is a side elevational view of a portable power tool unit looking from the side of the same and showing my new design.

Fig. 2 is a front elevational view of the same, and

Fig. 3 is a top plan view thereof.

The distinctive feature of the design for portable power tool unit illustrated is the configuration of the portion of the portable power tool unit above the cylindrical casing as best seen in Figures 1 and 2.

I claim:

The ornamental design for a portable power tool unit, substantially as shown and described.

ALONZO G. DECKER.
